Primary Examiner — Amy C Wierenga*Assistant Examiner* — Jamaal Rasheed(74) *Attorney, Agent, or Firm* — Wenderoth, Lind & Ponack, L.P.(57) **CLAIM**

The ornamental design for a pressure balancing valve, as shown and described.

DESCRIPTION

FIG. 1 is a perspective view of a pressure balancing valve embodying our new design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom plan view thereof.

The broken lines illustrate portions of the pressure balancing valve that form no part of the claimed design.

1 Claim, 7 Drawing Sheets(56)
